COMBINATION JOURNAL STOP, OIL SEAL, DUST GUARD

David S. Campbell, Glen Ellyn, Ill., assignor to Cardwell
Westinghouse Company, a corporation of Delaware

Filed Oct. 1, 1957, Ser. No. 687,389

8 Claims. (Cl. 286—6)

This invention relates to a combination journal stop, oil seal, and dust guard assembly; and while the arrangement offers important individual features such as an improved journal stop and an improved seal, the structures that embody each of these features are combined in a novel manner to produce a novel unitary assembly.

The principal objects of the present invention are: the provision of a simplified assembly for ready insertion in the dust guard wells of existing journal boxes to achieve a simplified journal stop construction, to elevate the effective oil retaining level of the dust guard well, and to utilize the dust guard itself for supplementing the oil retaining action; the provision of a novel journal stop configuration for minimizing friction and wear due to contact between the journal and the stop; and the provision of an improved dust cap of simple and inexpensive construction for sealing the open top of the dust guard well after the present assembly is in place.

Other objects and advantages will become apparent during the course of the following description.

In the accompanying drawings forming a part of this specification and in which like numerals are employed to designate like parts throughout the same,

Fig. 1 is a side sectional view through a conventional journal box showing the novel assembly of the present invention located in the dust guard well;

Figs. 2 and 3 are sectional views taken substantially on the lines 2—2 and 3—3, respectively, of Fig. 1;

Fig. 4 is a plan sectional view taken through the dust guard well area of the journal box; and

Fig. 5 is an exploded perspective view of the parts of the novel assembly illustrating their construction and relative mounting relationship.

Referring now to the drawings, the novel assembly of the invention is shown mounted in the familiar dust guard well region 10 of a typical present-day journal box 11. The dust guard well is defined by outer and inner walls 12 and 13, respectively, with these walls being formed with generally aligned openings for receiving a journal 14 that extends through the dust guard well and into the journal box for supporting the usual journal brass or bearing (not shown). The floor 15 of the journal box cooperates with the inner wall 12 of the dust guard well to define a reservoir for lubricant, with the effective retaining level of this reservoir usually being at the point indicated by the dotted line 16 as determined by the height of the lower lip of the inner wall 13.

Any desired form of lubricator (not shown) may be located in the journal box for continuously supplying lubricant to the rotating journal in the usual manner.

The various parts of the novel assembly of the present invention, as best seen in the perspective view of Fig. 5, comprise outer and inner plate-like journal stop members 20 and 21, respectively, and a plate-like spacer member 22 that is sandwiched between the plates 20 and 21. Each of these members is formed with a central opening in general alignment with the openings in

2

the inner and outer walls of the dust guard well for receiving and encircling the journal 14.

Journal stop member 20 consists of a centrally apertured plate 23 and fore and aft spaced journal stops 24. The stops are mounted on the plate in laterally offset relation thereto and are positioned on opposite sides of the opening through this member for flanking relation with the journal. Similarly, member 21, which is of the same general configuration as member 20, comprises a plate 25 that carries fore and aft spaced journal stops 26 in laterally offset relation.

The journal stops themselves may be of malleable iron or brass or bronze or an alloy of aluminum, or may even be of a Bakelite type of material or of any other material that exhibits the characteristic of high-impact strength and that is softer than the material of the journal to avoid scoring of the journal. The plates which carry the stops may be of a Bakelite type material to facilitate forming a secure joint between the stops and the plate, although it is preferred to utilize a material for the plate and the stops that will permit of forming a one-piece structure.

The journal stop members 20 and 21 are constructed for insertion in the dust guard well to cooperate respectively with the outer and inner walls 12 and 13 in controlling fore and aft movements of the journal relative to the journal box. It is preferred that the size and shape of these plate-like members be generally similar to the size and shape of the walls with which they cooperate except that the openings in the plates 23 and 25 are slightly narrower than the openings in the corresponding walls so that the opposite marginal edges of the plates and their associated journal stops project beyond the opposite marginal edges of the walls adjacent thereto. The laterally offset stops are thus arranged to overlap the laterally extending vertical edges that bound the opening through the associated wall for abutment against these edges in resisting fore and aft movement of the journal. Preferably, the stops are of the same thickness as the wall that is adjacent thereto so that the stops lie flush with this wall.

When sharp impacts, such as arise during switching and humping operations bring the journal into contact with the stops, the forces of reaction, through the medium of the stops, are borne by the walls of the dust guard well. In this connection, the supporting plates for the stops are mounted in the dust guard well with a limited freedom of movement to avoid the imposition of severe loads either on the plates themselves or on the joint between the plates and the stops.

The spacer member 22, which is interposed between the journal stop members 20 and 21 to maintain the journal stops in place in substantially flush alignment with the walls of the dust guard well, is in the form of an annular plate 27 that may be of fibreboard or a Bakelite type material provided with a circular opening of such diameter as to allow a clearance on the order of $\frac{1}{32}$ " with the journal. Thus this spacer plate 27 rides with the journal in the manner of the familiar dust guard arrangements. The mounting arrangement of the present assembly within the dust guard well is sufficiently free to accommodate the movement of the dust guard plate without developing excessive wear on the parts.

In mounting the plate assembly of Fig. 5 in a dust guard well, member 21 is first inserted downwardly through the open top of the well and into its operative position adjacent the inner wall 13; then member 20 is inserted in a similar fashion into operative position adjacent the outer wall 12; and, finally, the spacer or dust guard plate is inserted between the journal stop mem-

bers 20 and 21 to maintain them in their intended location.

When the assembly is once installed, the journal stop members 20 and 21 are effectually locked in place and resist displacement such as might be caused by fore and aft shifting of the journal relative to the journal box. As described previously, the journal stops engage against the vertical edges of the walls adjacent thereto to resist fore and aft movements of the journal, and this engagement necessarily serves to limit fore and aft movements of the plates 23 and 25.

For a complete locking arrangement, it is also necessary to provide against vertical displacement of the journal stop members such as might be caused by vertical shifting of the journal relative to the journal box. As best seen in Fig. 3, the stops 24 carried by the plate 23 that is associated with the outer wall 12 of the dust guard will also interlock with this wall in the vertical direction so that upon relative vertical movement between the stops and the wall adjacent thereto, the stops will immediately engage against the wall and block such movement. While no similar vertical interlocking exists in the case of the stops 26 carried by plate 25, none is actually necessary since the interlocking action of plate 23 and its stops 24 will preclude the possibility of the journal causing a vertical displacement of plate 25. If desired, however, the stops 26 could be extended upwardly as indicated in phantom lines at 28 in Fig. 2 to develop a similar vertical interlocking action for plate 25.

While the journal stops 24 and 26 may be given any desired surface configuration, such, for example, as the well-known flat, vertically extending arrangement, they are preferably arranged to provide a relatively broad surface area for contact with the journal in order to minimize wear and to limit concentrated heat generation during the time of such contacts. For this purpose, each stop has a substantially flat journal-engaging surface portion extending vertically a slight distance above and below the horizontal plane of the axis of the journal (see bracketed regions 29 in Figs. 2 and 3) and a vertically-extending, smoothly-curving surface portion (see bracketed regions 30 in Figs. 2 and 3) located beneath and merging smoothly with the flat portion. The curving portions 30 bend inwardly toward the axis of the journal; but, since their rate of curvature is less than the rate of curvature of the surface portion of the journal that is adjacent thereto, the clearance between the stop and the journal increases in the downward direction. While, with this specific configuration for the journal stops, a line contact initially may exist between the journal and the stops, after a very few interactions between these parts, the journal stop, because of its softer material, will yield slightly to provide a surface that is substantially complementary to the surface of the journal. At this time the curving surface portions 30 play a more active part and cooperate with the originally flat surface portions 29 to establish a broad surface area of contact.

The journal stop and dust guard plate assembly lends itself to the provision of an oil seal for more effectively retaining lubricant in the reservoir formed in the bottom of the journal box. As mentioned previously, the effective retaining level of the reservoir is usually at the level indicated by the dotted lines designated 16 in Fig. 1, this level being determined by the height of the lower lip of the inner wall 13. While in the usual journal box arrangement it is considered best practice to fill the reservoir to a height of approximately 1", as indicated by the dotted lines designated 32 in Fig. 1, which is slightly beneath the effective retaining level 16, it is nevertheless important to limit loss of oil due to splashing by raising the effective retaining level for the reservoir.

According to the present invention, this may be accomplished by providing the plate 25 with an arcuate

sealing lip 33 for establishing liquid-tight engagement with the lower periphery of inner wall 13 of the dust guard well. The sealing lip itself is preferably of neoprene or a similar type of material that may readily be securely bonded to the lower lip of its supporting plate, and it consists of horizontal and vertical legs 34 and 35, respectively, with the horizontal leg carrying the vertical leg 35 in outwardly spaced relation from the plate 25.

As best seen in Figs. 1 and 5, the vertical leg 35 is serrated along the surface 36 that is to establish sealing engagement with the inner wall 13. In addition, this vertical leg tapers downwardly to provide a space between it and the plate 25 in the form of a downwardly-converging slot and to ensure a more positive gripping action. While the sealing lip 33 raises the effective retaining level for the reservoir to the point indicated by the dotted line 37 in Fig. 1 and thus contributes importantly in eliminating loss of oil from the reservoir, its action may be supplemented by providing an annular sealing member 40 around the outer periphery of the spacer or dust guard plate 27. As best seen in Figs. 1 and 4, the periphery of plate 27 is formed with a V-notch 39 in which this supplementary sealing member 40 is seated to protrude laterally beyond the opposite faces of the spacer plate 27 as is appropriate for developing a proper seal with the adjacent faces of plates 23 and 25. The sealing ring 40 may comprise a length of hollow tubing 41, of neoprene or other similar material, through which a garter spring 42 is extended, with the garter spring being tensioned to secure the tubing 41 in the V-notch 39 and with the tubing 41 establishing sealing engagement with both plate 25 and plate 23. Alternatively, the sealing ring could be an ordinary O-ring or other comparable arrangement.

It will be apparent from a consideration of Fig. 1 that the oil which splashes above sealing lip 33 is blocked by the supplementary action of the sealing ring 40 so that the only possible point of egress for the oil is the slight clearance that exists between the journal and the dust guard plate 27. Thus, the plate assembly of the invention provides an effective oil seal for the reservoir of the journal box, in addition to providing the advantageous journal-stop arrangement.

For the complete protection of the plate assembly in the dust guard well, the invention includes a dust guard well cap for closing off and establishing a positive seal around the open top of the dust guard well. The cap is in the form of a hollow, inverted, pan-shaped member 43 of resilient sealing material such as neoprene, with the opposite ones of the side walls of the pan converging downwardly to enhance the sealing action of the pan around the top of the dust guard well. The side walls terminate in outwardly directed shoulders 44 that serve as a seat for a garter spring 45 that extends about the periphery of the cap side walls in tensioned relation to hold the side walls in sealing engagement with the inner and outer walls of the dust guard well.

From the foregoing description, it will be seen that the objects of this invention have been accomplished in that the simplified plate assembly is adapted for ready insertion in the dust guard well of a journal box to provide an improved journal-stop mechanism, to act as a dust guard, and to provide an effective oil-retaining seal for the dust guard well. It will be noted in particular that the journal stops are arranged to engage the journal at a region that does not affect the lubricating function and also at a region that does not come in contact with the journal brass or bearing so that even should the journal become scored or marred by the journal stops, this will not in any way impair its functioning.

It should be understood that the description of the preferred form of the invention is for the purpose of complying with Section 112, Title 35, of the U.S. Code and that the appended claims should be construed as broadly as the prior art will permit.

I claim:

1. In an assembly for mounting at the inner end of a journal box, said inner end including laterally spaced outer and inner walls defining a dust guard well, with said assembly being receivable in the dust guard well and forming a central opening for receiving a journal that extends through the well and into the box, said assembly including an inner plate-like member adjacent said inner wall and having a lower sealing lip engageable with the upper portion of the bottom end of said inner wall for raising the effective level thereof, and outer plate-like member adjacent said outer wall, and a dust guard engageable between said members; the improvement wherein said inner plate-like member has fore and aft spaced journal stops fixed thereon and offset laterally therefrom for engagement with oppositely facing vertical edges of said inner wall, said outer plate-like member has fore and aft spaced journal stops fixed thereon and offset laterally therefrom for engagement with oppositely facing vertical edges of said outer wall, and said dust guard has a laterally protuberant resilient ring about its outer edge in compressed sealing engagement between said members.

2. The arrangement of claim 1 wherein the journal stops on one of said members extend upwardly into adjacent abutting relation with the wall adjacent said one member for limiting upward displacement of said members by said journal.

3. In an assembly for mounting at the inner end of a journal box, said inner end including laterally spaced outer and inner walls defining a dust guard well, with said assembly being receivable in the dust guard well and forming a central opening for receiving a journal that extends through the well and into the box, said assembly including an inner plate-like member adjacent said inner wall and having a lower sealing lip engageable with the upper portion of the bottom end of said inner wall for raising the effective level thereof and spacing means engageable between said member and said outer wall for holding said member in said dust guard well; the improvement wherein said inner wall has fore and aft spaced journal stops fixed thereon and offset laterally therefrom for engagement with oppositely facing vertical edges of said inner wall.

4. In an assembly for mounting at the inner end of a journal box, said inner end including laterally spaced outer and inner walls defining a dust guard well, with said assembly being receivable in the dust guard well and forming a central opening for receiving a journal that extends through the well and into the box, said assembly including an inner plate-like member adjacent said inner wall, and spacing means engageable between said member and said outer wall for holding said member in said dust guard well; the improvement wherein said inner plate-like member has fore and aft spaced journal

stops fixed thereon and offset vertically therefrom for engagement with oppositely facing vertical edges of said inner wall.

5. In an assembly for mounting at the inner end of a journal box, said inner end including laterally spaced outer and inner walls defining a dust guard well, with said assembly being receivable in the dust guard well and forming a central opening for receiving a journal that extends through the well and into the box, said assembly including a plate-like member adjacent one of said walls, and spacing means engageable between said member and the other wall for holding said member in said dust guard well; the improvement wherein said plate-like member has fore and aft spaced journal stops fixed thereon and offset vertically therefrom for engagement with oppositely facing vertical edges of said one wall.

6. The arrangement of claim 5 wherein the journal stops on said plate-like member extend upwardly into adjacent abutting relation with the wall adjacent said member for limiting upward displacement of said member by said journal.

7. The arrangement of claim 5 wherein each of said journal stops has a substantially flat vertical journal-engaging surface portion extended above and below the region of the horizontal axis of said journal and a vertically extended curved surface portion beneath said flat surface portion and merging smoothly therewith, said curved surface portion being curved towards said journal with the rate of curvature of said curved surface portion being less than the rate of curvature of said journal.

8. A journal stop for mounting alongside a journal in a journal box to limit fore and aft movement of said journal relative to said box, said stop having a substantially flat vertical journal-engaging surface portion extended above and below the region of the horizontal axis of said journal and a vertically extended curved surface portion beneath said flat surface portion and merging smoothly therewith, said curved surface portion being curved towards said journal with the rate of curvature of said curved surface portion being less than the rate of curvature of said journal.
